ELECTRIC LANTERN

Bronislaw Zapolski, Princeton, N.J., assignor to Herbert J. Ashe, 1/2 The H. J. Ashe Company, South Norwalk, Conn.

Filed Dec. 23, 1968, Ser. No. 15,079

Term of patent 14 years

Int. Cl. D26—04

U.S. Cl. D48—24

FIG. 1

FIG. 2

FIG. 3

FIG. 4

FIG. 5

FIG. 6

FIG. 7

FIGURE 1 is a perspective view showing the front, one side and the top of my design for an electric lantern with the handle in the raised position;

FIGURE 2 is a side elevational view thereof;

FIGURE 3 is a bottom plan view thereof;

FIGURE 4 is a rear elevational view thereof;

FIGURE 5 is an elevational view of the other side than that shown in FIGURE 2;

FIGURE 6 is a view same as FIGURE 1 the handle being shown however in the lowered position; and

FIGURE 7 is a right side elevational view thereof.

I claim:

The ornamental design for an electric lantern, substantially as shown.
